CLAIM

The ornamental design for a shoe as shown and described.

DESCRIPTION

FIG. 1 is a bottom front perspective view of a shoe showing my new design;
FIG. 2 is a bottom view thereof; and,

FIG. 3 is a bottom rear perspective view thereof.
The broken line showing of the eight plus-sign-shaped tread elements within the shaded area form no part of the claimed design. The broken lines depicting the remainder of the shoe form no part of the claimed design.
